UNITED STATES PATENT OFFICE

LAURA V. ROONEY, OF WASHINGTON, DISTRICT OF COLUMBIA

LINGERIE CLASP

Application filed March 3, 1931. Serial No. 519,856.

The device forming the subject of the instant invention is primarily designed to connect the shoulder straps of underslips, or of other articles of women's underwear, to the underside of the shoulder portion of the outer garment and thereby prevent the discomfort and embarrassment which results from the slipping of said shoulder strap or straps off the shoulder of the wearer. Its primary purpose is to provide a device of this nature which will be of simple and inexpensive construction, may be easily attached to or removed from the outer garment, may be worn without its presence being noticed and without imposing any discomfort on its wearer, and may be very easily closed about the strap or straps which it encircles and easily opened to free it from said strap or straps, and, when closed, will be free from any tendency to open accidentally under any force resulting from movements of the wearer. This purpose is secured from a construction, such as that illustrated in the accompanying drawings, characterized in that it comprises a flexible body member of appropriate length to lie beneath and cross the strap or straps to be held against displacement, and having one of its ends suitably attached to a pin by which it is fastened to the outer garment adjacent the shoulder seam of the latter and its other end suitably attached to a member by which it is attached to the pointed end of the pin, and characterized further in that the latter member is formed to encase the pointed end of the pin and is engageable therewith and disengageable therefrom by relative endwise movement of said member and pin and, in the use of the clasp, will fully protect the wearer against any liability of being pricked by the pin.

In the said drawings, in all figures of which the parts are shown larger than they will ordinarily be produced in practice:

Fig. 1 is a side, or a plan, view of the clasp showing it in its open position;

Fig. 2 is a perspective view of the said clasp, showing its parts in the position they occupy when the pointed end of the pin is

inserted into its holding member but has not been secured;

Fig. 3 is a view which indicates the clasp attached to an outer garment and in holding relation with a lingerie strap; 55

Fig. 4 is a detail sectional view on the line indicated at 4 in Fig. 3;

Fig. 5 is a plan view, showing a part of the outer garment and a part of a lingerie strap connected to each other by my improved clasp; 60

Fig. 6 is a detail representation, on a larger scale than the preceding figures, showing in section one suitable construction of the member which encases and secures the pointed end of the pin; and 65

Fig. 7 is a similar enlarged detail representation showing in section a specifically different construction of encasing and securing member for the pointed end of the pin. 70

The body member of the clasp, marked A, in the accompanying figures of the drawings, may be of any suitable flexible material—such as tape, ribbon or the like, of either fabric or metal—and has one of its ends extending through a loop or eye 10, formed at one end of the pin, B, and secured, as by cross stitches 11, whereby this connection is of pivotal nature. The other end of the body A is similarly pivotally connected to the member C or C' which in the use of the clasp encases the pointed end of the pin. This member C or C' is engageable with and disengageable from the pin by endwise relative movement of the member and pin, and includes elements—such as those hereinafter described, for example,—which tightly grasp the pin and hold it against accidental displacement. Two embodiments, which differ from each other only in respect of the particular elements which grasp the pin, are shown in Figs. 6 and 7, respectively. All other elements being alike in both embodiments are respectively designated by like reference numerals, but different reference characters are applied in Figs. 6 and 7 to the elements, which correspond with, but are specifically different from each other. 85

Thus, in each embodiment, the member C 90

occupy when the pointed end of the pin is 95

or C', includes a head 12 having a loop 13 at one end through which the corresponding end of the member A is extended and appropriately secured,—as by cross stitches 14. This connection of the member A with the pin point encasing and holding member C or C' therefore is of pivotal nature. The head 12 is formed with an opening 15 and is provided with a sleeve, marked 16 in Fig. 6 and 16' in Fig. 7, which sleeve is fixedly secured to the head and has its opening in longitudinal alinement with said opening 15. Each embodiment also includes a barrel of substantially frusto-conical shape, marked 17 in all the figures. This barrel is slidable upon the sleeve, 16 or 16', and is under tension of a suitable spring 18 by which it is normally held in a retracted (pin holding) position with its inner end against the end of the head 12. Its outer end is formed with an opening, which is shown most clearly in Fig. 6, at 19, and is also shown, though undesigned, in Fig. 7. This opening in each embodiment is alined with the opening in the corresponding sleeve, 16 or 16', and affords access of the pointed end of the pin into the latter.

The correlation of the body member A, pin B, and pin encasing or securing member C or C' is such that after the pin B has been inserted in the flaps or free ends d, d' of the outer garment D, adjacent the shoulder seam d'', and the body member A has been extended under the lingerie strap E—35 or straps, if more than one strap is to be held—the pointed end of the pin may be inserted through the opening 19 at the outer end of the barrel 17 and through the sleeve 16 or 16' and into the opening 15 in the head 12.

In order that the pin, when its pointed end is seated in the member C or C', may be tightly grasped adjacent said pointed end by said member, means, under control 45 of said barrel 17, are provided to tightly grasp and thereby hold the pin against accidental displacement. The means referred to may be of any suitable nature. For example, in Fig. 6 a pair of balls, 20, are mounted in lateral openings formed in opposite sides of a flange 21 at the outer end of the sleeve 16 and are pressed into holding engagement with opposite sides of the pin by the outer end of the barrel 17, which latter, it will be noticed, is tapered and so correlated with the outer surface of the flange and balls that when the barrel is in its inward position the balls will be pressed tightly against the side of the pin and when 55 in its outward position, shown in Fig. 2 and indicated in dotted outline in Fig. 6, the pressure of the barrel upon the balls will be released. Accordingly, the barrel should be slid longitudinally outwardly upon the sleeve in the operation of inserting the pin

into the member and also in the operation of disengaging it from said member, so that in each of these operations the balls will be in the wider part of the barrel and hence will not interfere with the insertion or removal of the pin into and from said member. As soon as the pressure upon the barrel is released, the spring 18 retracts the barrel and, if the pointed end of the pin has been inserted, causes the balls to be forced into holding engagement with the pin.

The embodiment illustrated in Fig. 7 differs from that already set forth in that the holding elements are flexible fingers 20' 80 formed by slitting (as shown at 21') the flange formed at the outer end of the sleeve, which sleeve is marked 16' in this figure.

It will be noticed that in both exemplified embodiments of the invention the barrel 17 is of gradually lessening diameter toward its outer end, to cause it to exert pressure upon the balls 20 or fingers 20' when in its inward position and to release said pressure in its movement to its outward position, and, in its said outward movement, to place its spring, 18, under compression between the flange at the outer end of the corresponding sleeve and the inner end of the barrel. The spring 18, in both embodiments, thus is operative to return the barrel 17 to its retracted position upon the corresponding sleeve as soon as the pressure imposed on said barrel by the user to move it outward, for the insertion or removal of the pointed end of the pin, has been released.

It will be apparent from the foregoing that I have provided a simple and eminently practicable lingerie clasp, so constructed that it need not be permanently secured, as by sewing it, to the outer garment, and on the contrary, may be quickly and easily attached by its pin temporarily to a garment with which it is to be used and at the same time will be free from all liability 110 of any discomfort arising from the use of a pin as its fastening element and of all liability of disconnection of the pin from its holding member.

Having thus described the invention what I believe to be new and desire to secure by Letters Patent, is:—

1. A lingerie clasp comprising a flexible body member, a pin connected to one end of the body member, and a member connected to the other end of the body member and formed to be engageable with and disengageable from the pointed end of the pin by longitudinal movement of the pin relatively thereto and including holding means movable relatively to the pin and adapted to releasably grasp the same.

2. A structure according to claim 1 in which said holding means includes a tensioned barrel longitudinally movable rela-

tively to the pin and elements engageable with and disengageable from the pin under control of longitudinal movement of the barrel.

5 3. The herein-described lingerie clasp, consisting of a flexible body member, a pin having at one end a loop into which an end of the flexible body member is linked, a member including a head having an opening and provided with a loop into which the other end of the body member is linked, and also including a sleeve projecting from the outer end of the head and provided with a flange at its free end, means carried
10 by said flange and movable into and out of holding engagement with the pin adjacent the pointed end, a barrel slidably mounted relatively to said means and having one end adapted to exert pressure on the same
15 to thereby force said means into holding engagement with the pin, and a tensioning spring mounted upon the sleeve and between said flange and the other end of the barrel, for holding said barrel normally in
20 the position in which it exerts pressure on said pin engaging means.

25 In testimony whereof, I have hereunto affixed my signature.

LAURA V. ROONEY.
